219,319

DISPLAY STAND OR SIMILAR ARTICLE

Thomas P. Rademacher, Medina, Ohio, assignor to McNeil Corporation, Akron, Ohio, a corporation of Ohio

Filed Oct. 22, 1969, Ser. No. 19,669

Term of patent 14 years

Int. Cl. D6—01

U.S. Cl. D80—9

FIG. 1

FIG. 2

FIG. 3

FIG. 4

FIG. 5

FIG. 1 is a perspective view of a display stand embodying my new design.

FIG. 2 is a top plan view thereof.

FIG. 3 is a side elevational view thereof.

FIG. 4 is a side view in section taken substantially on line 4—4 of FIG. 1.

FIG. 5 is an end view thereof.

I claim:

The ornamental design for a display stand or similar article, as shown.

UNITED STATES PATENT OFFICE
CERTIFICATE OF CORRECTION

Patent No. Design No. 219,319 Dated November 24, 1970

Inventor(s) Thomas P. Rademacher

It is certified that error appears in the above-identified patent and that said Letters Patent are hereby corrected as shown below:

Column 1, lines 5 to 7, cancel "Fig. 4 is a side view in section taken substantially on line 4-4 of Fig. 1. Fig. 5 is an end view thereof." and insert -- Fig. 4 is a cross sectional view taken on line 4-4 of Fig. 1. Fig. 5 is a rear elevational view thereof. --.

Signed and sealed this 4th day of May 1971.

(SEAL)
